(List continued on next page.)

Primary Examiner—Mitchell Siegel

Assistant Examiner—Daniel Bui

(74) Attorney, Agent, or Firm—Michael J. McGreal

(57) **CLAIM**

The ornamental design for a dispenser, as shown and described.

DESCRIPTION

FIG. 1 is a perspective view of the dispenser of my design.

FIG. 2 is a front elevation view, the rear elevation view being a mirror image thereof.

FIG. 3 is a right side elevation view, the left side elevation view being a mirror image thereof.

FIG. 4 is a top plan view thereof.

FIG. 5 is a bottom plan view thereof.
